CLAIM

(57) The ornamental design for a headlamp, as shown and described.

DESCRIPTION

FIG. 1 is a perspective view of my headlamp;

FIG. 2 is a front view thereof;

FIG. 3 is a right side view thereof, the left side view thereof being a mirror image (except that it lacks the unclaimed feature shown in dashed lines);

FIG. 4 is a top view thereof; and,

FIG. 5 is a bottom view thereof.

The dashed lines in the figures represent environmental structure only and form no part of the claimed design.
